FIG. 1.

FIG. 2.

FIG. 3.

STEPHANIE WOJTECK

Inventor

By *Mildred W. W. W.*

UNITED STATES PATENT OFFICE.

STEPHANIE WOJTECK, OF KNOX, INDIANA.

INSOLE.

1,287,810.

Specification of Letters Patent. Patented Dec. 17, 1918.

Application filed February 20, 1918. Serial No. 218,232.

To all whom it may concern:

Be it known that I, STEPHANIE WOJTECK, a citizen of the United States, residing at Knox, in the county of Starke and State of Indiana, have invented new and useful Improvements in Insoles, of which the following is a specification.

The device which is the subject matter of the present application for patent is an insole adapted to be placed in a boot or shoe and embodying a structure whereby it is made to serve as an arch-support and a cushion.

The invention has for its object to provide a novel and improved device of the kind stated which is readily adjustable to properly fit the arch and also embodies other novel features of construction to be herein-after described in detail and claimed.

In order that the invention may be better understood, reference is had to the accompanying drawing forming a part of this specification.

In the drawing,

Figure 1 is a longitudinal section of the device showing its application;

Fig. 2 is a cross-section on the line 2--2 of Fig. 1;

Fig. 3 is a plan view of the device, and

Fig. 4 is a cross section on the line 4--4 of Fig. 3.

Referring specifically to the drawing, 5 denotes a fragment of a shoe having the usual outer sole 6, an inner sole 7 and a heel 8, all constructed and arranged in the customary manner for which nothing is claimed.

The supporting and cushioning device is a laminated unit composed of outer sheets 9 of leather and an inner sheet 10 of felt or other suitable fabric, and having a conventional outline to fit in the shoe. The device also has a transverse slant at the arch, with a lateral arch shield 11 on one side and an upstanding flange 12 on the opposite side to keep the foot from displacing the device sidewise. The device is positioned in the shoe above the inner sole 7, and it is held in place by two depending bottom studs 13 and 14 located near the respective ends of

the plate. These studs seat in apertures made in the inner sole 7, and the latter also has two or more apertures 15 back of the front aperture in which the stud 13 seats, so that if the wearer requires a higher arch, 55 the device may be flexed for this purpose, and the front stud inserted into one of the apertures 15, thus raising the arch to the desired height, the stud in its new location holding the device in its adjusted position. 60 It will be understood, of course, that the device has sufficient flexibility so that it may be adjusted as described, and at the same time it has sufficient inherent stiffness to support the arch. 65

At a certain part of the ball of the foot, the sensitive muscle often needs a support, and the device is therefore provided with an upward bulge 16 for this purpose.

The inner layer 10 of the device is provided with a large number of apertures, preferably circular, in which are inserted fillers or felt disks 17, which latter are removable. When any spot on the wearer's sole is tender, swollen or protuberant on account of bone formation, one or more of these disks may be removed so that a depression is formed in the top layer 9 of the device to take the pressure off the tender spot. The plies 9 and 10 are adhesively assembled or secured in any other suitable manner so that they may be separated for removal of the desired disks 17. 75

The top leather ply 9 is also crimped, as shown at 18, to form an upstanding part 85 designed to form a separator for the great toe from the adjacent toe, it being understood that the part 18 seats between said toes. The great toe can therefore be straightened out so as to counteract the 90 stress of a bunion located at the exterior part of the joint between the great toe and the ball of the foot.

I claim:

An attachment for boots or shoes, comprising a laminated plate having an inner layer provided with removable sections to produce depressions in the top layer. 95

In testimony whereof I affix my signature.

STEPHANIE WOJTECK.
